Primary Examiner — Darlington Ly*Assistant Examiner* — Daniel J Domino(74) *Attorney, Agent, or Firm* — Saidman DesignLaw Group, LLC(57) **CLAIM**

The ornamental design for a display screen or portion thereof with graphical user interface, as shown and described.

DESCRIPTION

The sole FIGURE shows a display screen or portion thereof with graphical user interface showing our new design.

The peripheral dashed broken lines illustrate a display screen or portion thereof, and form no part of the claimed design.

In sole FIGURE, the dotted broken lines illustrate boundaries which form no part of the claimed design, and portions within the dotted broken line form part of the claimed design; the portions between the dotted broken lines and the peripheral dashed broken lines form no part of the claimed design.
